A. C. MYERS

COLLAPSIBLE HAIRBRUSH

Filed March 8, 1922

UNITED STATES PATENT OFFICE.

ALFRED CLAYTON MYERS, OF ALTOONA, PENNSYLVANIA.

COLLAPSIBLE HAIRBRUSH.

Application filed March 8, 1922. Serial No. 542,074.

To all whom it may concern:

Be it known that ALFRED CLAYTON MYERS, a citizen of the United States, residing at Altoona, in the county of Blair and State 5 of Pennsylvania, has invented certain new and useful Improvements in Collapsible Hairbrushes, of which the following is a specification.

This invention relates to toilet articles and 10 more particularly to an improved collapsible hair brush that is adapted to open and close similar to a book, whereby it may be carried in a vest pocket, or attached to the end of a watch chain and occupy a space 15 not greater than small articles usually carried in one of the waist-coat pockets.

A primary object of the invention is to 20 provide a collapsible hair brush, constructed such that the bristles forming the brush are positioned in bars that are adapted to rotate sufficiently to cause the bristles to occupy a vertical position when the brush is open, and to occupy a horizontal position when the 25 brush is closed.

Another object of this invention is to 30 provide means whereby the brush bars are readily removed when soiled or worn out, and replaced by new ones, thus maintaining at all times a sanitary toilet article.

A further object of this invention is to 35 provide a combined brush cover and handle which, when the brush is closed, acts as a cover for the ends of the bristles, and when open acts as a handle that is adapted to be held when using the brush on the hair.

With these and other objects in view 40 which will more readily appear as the nature of the invention is better understood, the same consists in the novel construction, combination and arrangement of parts as will be hereinafter fully pointed out, illustrated and claimed.

It will of course be understood by those 45 skilled in the art to which this invention belongs that the same is quite susceptible to a variety of structural changes and modifications without departing from the spirit or scope of the invention, but a preferred and practical embodiment of the invention is shown in the accompanying drawings, in which:

Figure 1 is a plan view of my improved brush, showing the same in an open position.

Fig. 2 is an end elevation of the parts 50 shown in Figure 1.

Fig. 3 is an edge view of the parts shown in Figure 1 of the drawings.

Fig. 4 is an end view of my improved brush as it appears in a folded or collapsed position.

Fig. 5 is an elevational view of a cap that is adapted to be attached to the end of the two center bars of the brush.

Fig. 6 is a plan view of the parts shown in Figure 5 of the drawings.

Figure 7 is a plan view of the cap used on the end of the two center bars.

Fig. 8 is an elevational view of the end cap used on the intermediate and outside brush bars.

Fig. 9 is a plan view of the parts shown in Figure 8.

Fig. 10 is a plan view of the end cap used on the opposite end from the one on which the cap shown in Figure 8 is used.

Fig. 11 is a part plan view of one of the brush bars showing the tenon which engages the end cap.

Fig. 12 is an end view of the parts shown in Figure 11 of the drawings.

Similar reference characters designate corresponding parts throughout the several figures of the drawings.

In carrying the present invention into effect it is proposed to provide a foldable brush device consisting of a relatively collapsible or folding pair of casing sections A and B, the same being adapted to open and close after the manner of a book and provided at their free edges with the supplemental cover members H hinged thereto as at z in any convenient and suitable manner.

As shown in the drawings the said sections A and B are preferably pivotally or hingedly connected by the hinge members C 95 which may be in the form of the plates 1 having the internally threaded bosses 2 projecting from the outer faces thereof to fit into corresponding sockets in the inner side walls of the members A and B while the inner face thereof is provided with the mutilated gear portions 3 and the vertical slots 4 for receiving the medial brush bar unit D. This unit D preferably consists of the brush bars E and E' connected by the web portions F and the said bars having at the ends thereof the keys or tenons 5 for fitting into the slots or sockets 4. For the purpose of holding the bosses 2 in the socket of the end walls of the casing sections A and B 105

into which they fit the screws or other fastenings 6 may be provided.

It will thus be apparent that when the screws 6 are fitted into the internally screw threaded portions of the bosses 2 so that the hinge members C connect the members A and B, the latter may readily swing toward each other through an arc of 180° so that the faces a and b thereof may come 10 into contact. Also, as shown the corner portions c² of the sections A and B may be provided with intermeshing teeth as shown.

When the brush bar unit D is fitted to the hinge members C it will be apparent 15 that the said brush bars constitute in effect the continuation of the axes of the pivot screws 6, and constitute more or less the pintles of the hinging structure. The brush bars E and E' carry the radially projecting 20 bristles or the like G which project therefrom radially and always remain in that position, so that when the sections A and B are folded toward each other the bottom walls thereof will be parallel with the bristles G as shown in Figure 4.

Additional relatively shiftable brush bars E² are carried in the sections or wings A and B of the brush. These brush bars E² have the bristle units G' also projecting 30 therefrom, and for the sake of lightness may be of the corrugated or serrated formation shown in the drawings. The opposite ends of the brush bars E² are fitted with the end caps 7 which have the slots 8 for 35 detachably receiving the tenons 9 of the brush bars, thereby permitting of the detachment and replacement of the bars when desired, and the said end caps 7 are also provided with the offset journal bosses 10 which are interiorly threaded to receive the 40 pivot screws 11. These cap members 7 together with their bosses and the screws 11 are similar to the corresponding portions of the hinged member C but are different 45 therefrom in the respect that they are rotatable to thereby circumferentially shift the brush bars E². In that connection it will be observed that in order to effect such a movement the periphery of the caps 7 are 50 provided with a mutilated gear portion 12 which is adapted to engage with the shiftable rack 13. The said rack 13 is slidable in a guide-way 14 in the inside face of the end wall of the casing section and intermeshes at one end with the mutilated gear 55 portion 3 of the hinge member C. Obviously, a rack 13 may be provided for each section of the brush, and when the said sections A and B are moved toward each other 60 with the pivot 6 as an axis, the racks 13 will be drawn toward the inner edges of the sections and thereby have the effect of rotating the caps 7 which carry the bars E² thereby to also cause them to move through an arc

of substantially 90° to bring the bristles or 65 spines G' carried thereby into the position shown in Figure 4 of the drawings.

From the foregoing it will be understood 70 that the present improvement aims to provide a foldable or collapsible brush where in the intermediate brush bars remain stationary or fixed while the wings rotate about the fixed axis of said bars so that through the medium of the gear teeth 3 on the hinged members and the racks 13 which 75 engage with the teeth 12 of the end caps of the rotary brush bars, all of the bristles or spines of the brush may be brought into alignment when one section is folded toward the other.

Without further description it is thought 80 that the features and advantages of the improvement will be readily apparent to those skilled in the art and it will of course be understood that changes in the form, proportion and minor details of construction 85 may be resorted to without departing from the spirit of the invention or scope of the appended claims.

I claim:—

1. A folding brush construction including 90 a pair of box-like casing sections, hinge members for connecting the adjacent sides of said sections, said hinge members each including a pivot axis about which the sections rotate, a duplex brush-carrying bar detachably fitted to said hinge members, gear teeth formed on said hinge members, a plurality of rotatable brush bar carrying members journaled in the side wall of the 100 casing and each being provided with gear teeth, rack bars slidably guided in each section and meshing with the gear teeth of said hinge members whereby relative movement of the sections on the hinge member will cause the rotation of said journal members, and brush carrying bars carried by said journal members.

2. A folding brush construction including 110 a pair of casing sections, means for pivotally connecting the sections, a fixed brush unit having radially projecting bristles arranged at the hinging axis of the sections, a plurality of relatively rotatably supported brush bars arranged parallel to the said stationary brush bar and carried by the said sections, and means engaging with the rotatable brush bars and also with the relatively fixed hinge means whereby movement 115 of one section relative to the other will cause the brush bars to move and thereby bring the bristles of said bars into alignment with the bristles of the relatively stationary brush bars.

In testimony whereof he affixes his signature.

ALFRED CLAYTON MYERS.
